UNITED STATES PATENT OFFICE

WILLIAM C. STEVENS, OF NEW YORK, N. Y.

CLOTHES HANGER

Application filed December 7, 1928. Serial No. 324,507.

The present invention relates to garment hangers and more particularly to a hanger adapted to display garments such as dresses and the like.

Garment hangers have been made in various forms, both from metal and from wood. The purpose of these hangers is to provide a member fitting into the shoulders of a garment to hold it in position so that it can be stored without wrinkling. In some cases the hangers have attachments for suspending trousers, in other cases, there are devices to stretch the fronts of coats outwardly during storage to avoid sagging.

The present hanger is adapted both for storing garments in show cases and for displaying them to prospective customers. It is particularly useful in department stores, factories, and showrooms, where dresses are placed on hangers side by side in cases or in storage rooms and are repeatedly removed for inspection by prospective customers.

When a garment such as a dress is placed on the usual clothes hanger it folds along two lines at diametric sides of the dress, making it substantially flat. This gives to the dress a width substantially greater than that which it has when being worn. Due to the fact that women want small dresses, this is a handicap in the sale of such garments, because the dress looks larger than it really is. Various attempts have been made to avoid this by pinning the back of the dress in such a way as to reduce its width. Where the dresses are displayed almost continuously, pinning and unpinning the dress is considerable trouble and requires careful and skillful manipulation. In many instances, models put on one dress after another so that customers may see the actual appearance of the garments. This requires the constant attendance of models; in addition, putting on and taking off the dresses consumes considerable time and tends to soil the garments.

The present invention aims to eliminate the above difficulties by providing a garment hanger which is adapted to hold the dress flat when stored in a case or in a showroom, and which has means thereon permitting ready manual manipulation, during the display of

the dress on the hanger, to make it conform substantially to the shape it assumes when being worn.

An object of the present invention is to provide an inexpensive hanger for garments such as dresses and the like, adapted to facilitate display of the garments to prospective customers.

Another object of the invention is to provide a hanger readily adapted to improve the appearance of the garment during the display thereof.

Another object of the invention is to provide a hanger for a garment adapted to be manipulated to give to the garment substantially its natural shape during display thereof.

A further object of the invention is to provide a hanger having manually operated means, adapted to cause a dress or the like to take substantially the shape it assumes when being worn; and to position said manually operated means so that it may be operated by the hand holding the hanger during the display of the dress.

Other and further objects of the invention will be obvious upon an understanding of the illustrated embodiment about to be described or will be indicated in the appended claims, and various advantages not referred to herein will occur to one skilled in the art upon employment of the invention in practice.

A preferred embodiment of the invention has been chosen for purposes of illustration and description and is shown in the accompanying drawings, wherein

Fig. 1 is a perspective view showing the normal position of the pivoted loop in full lines and showing the position assumed in the display of the dress in dotted lines;

Fig. 2 is an enlarged sectional view along the line 2—2 of Fig. 1;

Fig. 3 is a front view of the hanger with a dress thereon as it appears while being displayed, the dotted lines showing the shape of the dress when in its normal position on the hanger; and

Fig. 4 is a top plan view of the hanger and dress, shown in Fig. 3.

Referring more particularly to the draw-

ings, there is shown in Fig. 1 a hanger comprising a curved member 1 adapted to fit into the upper part of a garment, the ends of the member extending substantially from shoulder to shoulder, with the usual hook 2 extending upwardly from the central portion thereof. Such a hanger may be used for various types of garments such as dresses, waists, coats and the like, to suspend the garments substantially flat so that a maximum quantity may be stored in minimum space.

On the lower side of the member 1 there are a pair of eyelets 4 screwed into the member 1 at substantially equidistant points on the respective sides of the hook 2. The loop 5 may be formed from a suitable wire or metal rod having a U-shaped lower portion with the upper ends thereof extending through the eyelets 4 and secured to each other in any suitable manner, for example, by extending one end through a loop 6 formed in the other end of the wire at substantially the center of the hanger. In order to facilitate manipulation of the loop there is provided an arm 7 preferably by extending on one end of the wire forming the loop 5 upwardly above the member 1. The end of the arm 7 may be bent upon itself, as shown at 8, to form a convenient grip for manipulating the loop. The arm 7 is also adapted to engage the member 1 to limit the movement of the loop 5 toward the front of the garment.

In operating the device, the hanger is placed in a dress as shown in Figs. 3 and 4. Under normal conditions the loop 5 rests substantially in a vertical plane and permits the dress to lie substantially flat so that it may be readily displayed as heretofore. When the dress is removed from the storage room to be exhibited to a customer, the salesman usually grips the central portion of the hanger, as shown in Fig. 3, with his thumb resting against the extension 7 of the loop 5. When the dress is held up for the customer to view, the extension 7 is pressed downwardly to force the lower part of the loop backwardly as shown in Figs. 1 and 2. The pressure outwardly on the back of the dress causes it to assume the shape shown in Figs. 3 and 4 instead of the flat shape which it had in the showcase, as shown in dotted lines in these two figures. The result is that the bodice of the dress assumes substantially a form which gives it the shape that it would have on a wearer. This gives to the dress its normal width instead of an apparently greater width caused by the dress being folded flat on diametric lines.

By means of the present hanger, it is possible, without extra time or trouble, to approximate the appearance that the dress has on a model. There is no likelihood of the dress being soiled because the salesman showing the dress does not have to touch it. The loop shapes the dress. The loop is positioned so

that the extension 7 may be engaged by the hand holding the hanger and hence, the device can be operated by the hand holding the dress and hanger.

It will be seen that the present invention provides a hanger which is simple in construction and inexpensive to manufacture. The hanger is particularly adapted for the display of garments such as dresses, and permits a salesman to hold the dress out with one hand and cause it to assume the shape which it has on an individual. It eliminates the necessity of exhibiting to a customer a dress which appears to be much larger than it actually is. The hanger causes the dress to appear its normal size. After the dress has been inspected the loop drops into substantially a vertical plane and permits the dress to be stored without taking up additional space in the storage room.

As various changes may be made in the shape of the loop or in the construction thereof, for example, the ends of the loop might be welded together with a suitable extension for manipulation formed therein, and as various other changes may be made in the form, arrangement and construction of the parts without departing from the spirit of the invention, it is to be understood that all matter herein is to be interpreted as illustrative and not in a limiting sense.

Having thus described my invention, I claim:

1. In a device for displaying garments such as dresses and the like, the combination of a member for supporting a garment, and a loop pivoted to said member and adapted normally to rest substantially in the plane of the hanger, said loop having an integral, protruding end extending upwardly to permit the hand holding said member to engage said end and to manipulate said loop.

2. In a device for displaying garments such as dresses and the like, the combination of a member for engaging and holding a garment, a wire loop mounted to oscillate with respect to said member, one end of the wire forming the loop extending upwardly to be engaged by the hand holding the member fitting into the garment to move said means in position to press the back of the dress temporarily outward to shape the bodice of the dress into a substantially circular form.

3. In a device for displaying garments such as dresses and the like, the combination of a hanger for supporting the garment, eyelets attached to said hanger, and a loop extending through said eyelets adapted to oscillate with respect to said hanger, the ends of the wire forming the loop being joined along the upper side of the loop with one end thereof protruding to be engaged by the hand to oscillate said loop with respect to the hanger.

4. In a device for displaying garments such as dresses and the like, the combination of a

hanger adapted to fit into the upper part of the garment for suspending same, a loop pivoted to said hanger and extending downwardly therefrom adapted normally to hang in substantially a vertical plane, the ends of the member forming the loop being joined at the upper part thereof with one end protruding to form means for tipping the loop.

5. In a device of the class described, the combination of a hanger for garments, a loop positioned substantially centrally with respect to said hanger and adapted to be oscillated with respect to said hanger, the ends of the member forming the loop being joined at the upper part thereof with one of the ends of the member being extended to form a means for engagement by the hand of the person holding the hanger to tip the loop.

6. In a device of the class described, the combination of a hanger for garments, means pivoted under said hanger adapted to press outwardly the back of the garment, a member integral with and extending upwardly from said means on one side of the hanger, said member being adapted to engage the hanger to limit the movement of said means toward the center of the garment.

7. In a device of the class described, the combination of a garment hanger having a horizontal supporting member, a hook attached to said member, eyelets secured in the bottom of said member to serve as bearings, a wire loop extending through said eyelets, one end of the loop being bent about the other to provide a free integral extension for tipping the loop, the end of said extension being bent to facilitate application or pressure thereto and being adapted to rest against said member adjacent the base of the hook to facilitate operation thereof and to limit the backward movement of the loop.

WILLIAM C. STEVENS.
